UNITED STATES PATENT OFFICE.

MELVIN B. WHEELOCK, OF CLEVELAND, OHIO, ASSIGNOR OF ONE-HALF TO ARTHUR A. WHEELOCK, OF CLEVELAND, OHIO.

VAPORIZER FOR INTERNAL-COMBUSTION ENGINES.

Application filed July 1, 1925. Serial No. 40,826.

This invention relates to an attachment for internal combustion engines, which is designed to increase the efficiency of such engines and to economize in the consumption 5 of fuel, by effecting a substantially complete vaporization of the fuel prior to its entry into the engine cylinders.

A further object is to facilitate the starting of a cold engine by providing means for 10 applying heat to a small body of liquid fuel retained between the carburetor and the fuel inlet of the engine to supply completely vaporized fuel to the cylinders in starting.

A further object is to provide an attachment 15 capable of effecting the results above-mentioned, which can be manufactured at small cost and which is adapted to be attached to the engine without modifying any of the structural parts thereof.

20 With the above and other objects in view, the invention may be said to comprise the device as illustrated in the accompanying drawings, hereinafter described, and particularly set forth in the appended claims together with such variations and modifications 25 thereof as will be apparent to one skilled in the art to which the invention appertains.

Reference should be had to the accompanying 30 drawings, forming a part of this specification, in which, Fig. 1 is a side elevation, partly in section, showing the attachment secured in place between the carburetor and the inlet manifold of an engine; Fig. 2 is a front elevation of the attachment, 35 a portion of the bottom of the chamber being broken away and shown in section; Fig. 3 is a section on the line 3—3 of Fig. 2; and Fig. 4 is a section on the line 4—4 of Fig. 2.

40 Referring to the accompanying drawings, a portion of the inlet manifold of an internal combustion engine is shown in Fig. 1 and designated by the numeral 1. Fig. 1 also shows a carburetor 2, such as is ordinarily 45 provided for supplying the fuel mixture to the engine. The carburetor has an outlet portion provided with attached flanges 3 adapted to be secured to the attaching flanges 4 of the inlet manifold. The attachment embodying the present invention is 50 designed to be secured between the attaching flanges 3 of the carburetor 2, and the attaching flanges 4 of the inlet manifold 1,

no change in any of the structural parts of the engine being required.

55 The attachment consists of a tubular body portion 5 and top and bottom closure members 6 and 7, which are detachably secured to the upper and lower ends of the body portion 5. The top closure member 6 has an 60 integral upstanding flange 8, which has a marginal outline corresponding to that of the flanges 3 and 4 and which is adapted to be bolted between the attaching flanges 3 and 4 of the carburetor and manifold. The 65 opposite faces of the flange 8, which are engaged between the flanges 3 and 4, are flat, forming a fluid tight joint with the said flanges when bolted between them. The 70 opposite faces of the flange 8 are provided with circular depressions 9 and 10, the diameters of which correspond to the internal diameters of the carburetor outlet and manifold inlet openings and, between the two 75 depressions, the flange 8 is formed with an imperforate web 11 which cuts off the flow from the carburetor and the inlet manifold. Passages 12 and 13 extend from the inner 80 side of the cover plate 6 to the depressions 9 and 10 so that the gaseous mixture from the carburetor is caused to flow into the liquid collecting and vaporizing chamber formed by the tubular body 5 and closure plates 6 and 7 and the gaseous mixture which is delivered 85 into the engine cylinders is drawn into the inlet manifold from said chamber through the passage 13. The vaporizing chamber also forms an expansion and mixing chamber between the relatively restricted passages 12 and 13 in which there is additional vaporization of the liquid contained 90 in the fuel mixture and in which the larger particles of liquid are precipitated and collected in the bottom of the chamber.

95 At the bottom of the auxiliary vaporizing chamber, there is provided a closed chamber adapted to house a heating device, this chamber being formed by a cup-shaped stamping 14 which fits open side down, within the lower portion of the tubular body 5 and has outturned flanges 15 which are secured between the bottom plate 7 and the lower end of the tubular body 5. The stamping 14 is lined on its under side with a sheet 100 of asbestos or other suitable heat-resisting material 16 and an electrical heating coil 17

is mounted in the space between the stamping 14 and bottom plate 7. The heating coil 17 is connected with a suitable source of current which is preferably controlled by a switch 18.

In the operation of the engine, a liquid fuel is mixed with the air in the carburetor 2 and this mixture passes through the passage 12, down into the auxiliary vaporizing chamber. In this chamber a portion of the liquid contained in the fuel mixture collects upon the bottom plate 14, which is heated by the coil 17, current being supplied to the coil 17 during the operation of the engine. The liquid lying upon the heated plate 14 is rapidly vaporized and this vapor passes with the mixture into the manifold 1. The liquid collecting and vaporizing chamber serves to collect liquid particles carried along with the fuel mixture and to supply to the fuel mixture fuel in the form of vapor arising from the heated body of liquid on the plate 14. Thus the fuel delivered to the engine is in a state of substantially complete vaporization so that a maximum amount of power is obtained from a minimum amount of fuel. The fuel collecting and vaporizing attachment also provides means for facilitating the starting of a cold engine. When the engine is stopped, a small quantity of liquid fuel will remain in the vaporizing chamber and by operating the switch 18, to supply current to the heating coil 17, a short time before the engine is started, the shallow body of fuel upon the plate 14 will be quickly heated and vaporized to such an extent that there is an adequate supply of completely vaporized fuel ready to be drawn into the engine cylinders immediately upon starting the engine.

Having described my invention, I claim:

1. A vaporizer attachment for internal combustion engines comprising a chamber having a tubular body and upper and lower end walls, said upper end wall having a flange adapted to be secured between sections of a conduit extending from the carburetor to the inlet manifold of an engine, said flange being of a size to completely cut off the flow between said sections, there being separate passages formed in the flange and leading from the interior of the chamber to opposite faces of said flange whereby all of the fuel mixture is caused to flow into the chamber from the carburetor and from the chamber to the inlet manifold.

2. A vaporizer attachment for internal combustion engines comprising a chamber having a tubular body and upper and lower

end walls, said upper end wall having a flange adapted to be secured between sections of a conduit extending from the carburetor to the inlet manifold of an engine, said flange being of a size to completely cut off the flow between said sections, said upper end member having separate passages leading from the interior of the chamber to opposite faces of said flange whereby the fuel mixture may flow into the chamber from the carburetor and from the chamber to the inlet manifold, and means for heating the lower end wall.

3. A vaporizer attachment for internal combustion engines comprising a chamber having a tubular body and upper and lower end walls, said upper end wall having a flange adapted to be secured between sections of a conduit extending from the carburetor to the inlet manifold of an engine, said flange being of a size to completely cut off the flow between said sections, said upper end member having separate passages leading from the interior of the chamber to opposite faces of said flange whereby the fuel mixture may flow into the chamber from the carburetor and from the chamber to the inlet manifold, and means for heating the lower end wall, said lower end wall being hollow and having an electrical heating element therein.

4. A vaporizer attachment for internal combustion engines comprising a chamber having a tubular body and end walls detachably secured to the upper and lower ends thereof, said upper wall having an integral flange adapted to be secured between sections of the conduit extending from the carburetor to the inlet manifold of an engine, said flange having a thickened marginal portion adapted to fit between the attaching flanges of said sections and depressions in opposite faces within said marginal portions, said flange having a continuous imperforate web within said marginal portion, said upper end wall having separate passages leading from the interior of the chamber to said depressions, said lower end wall comprising a cup-shaped stamping adapted to fit open side down within the lower end of the tubular body and a cover plate secured to the lower end of the body, said stamping and cover plate forming a closed heating chamber, and an electrical heating element in said heating chamber.

In testimony whereof, I hereunto affix my signature.

MELVIN B. WHEELOCK.
